ABSTRACT

A new *Calibrachoa* plant designated 'KLECA20858' particularly distinguished by a semi-trailing plant habit, and orange flowers with red centers, is disclosed.

1 Drawing Sheet

1

Genus and species: *Calibrachoa* sp.
Variety denomination: 'KLECA20858'.

BACKGROUND OF THE NEW PLANT

The present invention comprises a new and distinct variety of *Calibrachoa*, botanically known as *Calibrachoa* sp., and hereinafter referred to by the variety name 'KLECA20858'. 'KLECA20858' originated from a controlled cross in August 2017 in Stuttgart, Germany between the female *Calibrachoa* parent 'KLECA18408' (U.S. Plant Pat. No. 33,129) and the proprietary male *Calibrachoa* 'CA-2015-6520' (unpatented). Progeny from the cross were planted and a single plant was selected in May 2018 in Stuttgart, Germany.

'KLECA20858' has been found to reproduce true to type in successive generations of asexual propagation in Stuttgart, Germany via vegetative tip cuttings.

SUMMARY

The following are the most outstanding and distinguishing characteristics of 'KLECA20858' when grown under normal horticultural practices in Stuttgart, Germany and Latina, Italy.

1. A semi-trailing plant habit; and
2. Orange flowers with red centers.

DESCRIPTION OF THE PHOTOGRAPH

This new *Calibrachoa* plant is illustrated by the accompanying photograph of a plant grown outdoors in Stuttgart, Germany. The photograph shows the whole plant, including the flowers and foliage and buds. The colors shown are as true as can be reasonably obtained by conventional photographic procedures. The photograph is of a plant that is 12-weeks-old, taken indoors in May 2019 in Stuttgart, Germany.

DESCRIPTION OF THE NEW VARIETY

The following detailed descriptions set forth the distinctive characteristics of 'KLECA20858'. The data which

2

define these characteristics were collected from asexual reproductions carried out in Latina, Italy. Data was collected on plants grown 15-weeks since potting in a greenhouse with no pinching and using BONZI. Color references are to
